UNITED STATES PATENT OFFICE.

HIRAM W. HAYDEN, OF WATERBURY, CONNECTICUT, ASSIGNOR TO HOLMES, BOOTH & HAYDENS, OF SAME PLACE.

ARGAND-LAMP BURNER.

SPECIFICATION forming part of Letters Patent No. 247,560, dated September 27, 1881.

Application filed November 22, 1880. (No model.)

To all whom it may concern:

Be it known that I, HIRAM W. HAYDEN, of Waterbury, in the county of New Haven and State of Connecticut, have invented an Improvement in Argand-Lamp Burners, of which the following is a specification.

In Letters Patent reissued September 5, 1871, No. 4,541, there is an Argand burner with a flat wick bent up into a cylindrical form, and is raised or lowered by a metal rack with teeth at the upper end. My present invention relates to the same class of burners, but it is especially intended for burners of a large size.

I make use of a wick-tube the upper portion of which is removable to give access to the wick, and the wick-raising rack is applied between the edges of the wick and is connected to a ring with teeth around the air-tube. The wick is properly placed by hand and pressed upon the teeth of the ring, after which the removable section of the wick-tube is replaced. The cone that directs the air to the base of the flame is made with an internal hanging flange that forms the proper guide to direct the air, and at the same time allows the body of the cone to be farther removed from the heat of the flame, and causes the ascending current of air to impinge upon the metal in such a way as to reduce the temperature of the burner. I also make use of a deflecting-button and a movable extinguishing-tube, that, when raised by a cam, comes into contact with the button and simultaneously extinguishes the light and confines any gases and vapors, so as to lessen the disagreeable smell when the light is put out. There is a supplemental air-distributer within the cone, that serves to proportion the drafts that pass to the flame, as hereinafter set forth.

In the drawings, Figure 1 is a vertical section of the burner complete. Fig. 2 is a plan of the same, with the chimney-holder, deflector, air-distributer, upper part of the wick-tube, and extinguisher-button removed. Fig. 3 is an elevation of the burner with the chimney-holder and cone removed; and Fig. 4 is a section of the removable portion of the wick-tube and the extinguisher-tube. Fig. 5 is a section at the line $x-x$ of Fig. 1.

The air-tube a is closed at the bottom end by the plate a^2 . Within the air-tube is a sepa-

rate tube, a' , with wings 2, the object of which is to insure the vertical movement of the air within the tube a . This tube may also have vertical slots in it, as at a^3 , and one wing may extend down to the plate a^2 , to support the tube a' . There is also a rod, b , attached at the bottom of the air-tube, and carrying at its upper end the button c .

The metal of the air-tube, near the lower end, is slit upwardly a sufficient distance to form the lateral air-inlet by bending the metal outwardly a sufficient distance to reach the wick-tube d , in which wick-tube there is an opening, and the plate a^2 forms the bottom of this lateral air-inlet, and there is a plate between the air-tube a and wick-tube d to form the top of the air-inlet. The parts are soldered or otherwise attached together.

The burner-screw e and the gallery f are both attached to the lower end of the wick-tube d .

The wick-raiser is made of a band, i , around the air-tube a , having outwardly-projecting teeth, and to this band i the rack o is permanently fastened.

Through the metal forming the top and bottom of the lateral air-inlet there are openings, and the rack o passes through these openings and slides in and is guided by these portions of the burner. By this construction the rack o is at that portion of the burner where the lateral air-inlet is provided for the central air-tube; hence said rack is between the edges of the flat wick when entered in a bent condition into the burner, and this also allows the wick-raising wheel h to be introduced within this lateral air-inlet to act by its teeth in the row of holes in the rack, and raise or lower the same and the wick-raising ring i .

The axis of the wick-raising wheel h is supported at one end in the bracket 3, and near the button-head by the gallery f , through which said axis passes.

The upper portion, k , of the wick-tube is movable. It screws into the lower portion of the wick-tube; hence when the part k is removed the wick is exposed, and can be applied properly upon the teeth of the band i , and the screwing on of the portion k holds the wick to the teeth.

The upper end of the wick-tube is slightly

contracted, so as to set closely around the wick, and around the said wick-tube *k* there is the supplemental air-distributer *l*, formed of a perforated ring, which serves to steady the current of air that ascends outside the wick-tube, and this air-distributer also steadies the removable cone and chimney-holder.

The extinguisher is formed of a tube, *m*, surrounding the wick-tube and sliding freely thereon. There is a leg, *6*, that is attached to the tube *m* and passes downwardly through the guide-slide 7 upon the air-distributer *l*; and there is a cam-shaped arm, *o'*, that projects from a short rock-shaft, *8*, having its bearings 15 at the gallery *f* and in the support 18, and a crank-handle, *9*, or button outside the gallery, by means of which the cam is moved to act against the bottom end of the leg *6* and raise that and the extinguishing tube or sleeve *m* 20 until the upper end comes against the button, as shown by dotted lines in Fig. 3, so as to effectually stop the currents of air and cause the flame to be extinguished. At the same time the gases or vapors that are so objectionable when a lamp is blown out are confined so long as the extinguisher is kept up against the button.

When the cam-arm is liberated it and the extinguisher fall by gravity.

30 The cylinder *s* rests upon the gallery, and the lower part is perforated at 10 to form an air-distributer, and the upper part is slotted to form a spring chimney-holder, *12*.

The cone or deflector *t* is attached at its base to the cylinder *s*, and it is perforated at 35 13 to allow air to pass outside the deflector and within the chimney. The upper end of this deflector is contracted and formed with an internal hanging flange, *u*, against which the 40 ascending currents of air impinge, and thereby keep the cone or deflector cool, and this hanging flange, being nearly cylindrical, forms a guide to direct the air vertically upon the base of the flame.

45 I am aware that a lamp has been made with a removable section to the wick-tube and with a wick-raising ring having teeth on the top edge, as in English Patent No. 3,104 of 1862. In this case there is difficulty in introducing 50 the wick, and in causing the points to penetrate the same, because the wick has to be passed down inside of the ring, and then spread outwardly and pressed down upon the points. By my improvement the wick, being outside 55 of the wick-raising ring, can be opened and moved up or down and simply pressed against the projecting points of the ring when the wick is in the proper position, thus greatly facilitating the adjustment of the wick.

60 I claim as my invention—

1. In an Argand-lamp burner, the wick-raising

ring having outwardly-projecting teeth, and sliding upon the wick-tube, in combination with the rack passing downwardly across the lateral air-inlet to the air-tube, and the ratchet-wheel placed in said air-inlet, substantially as set forth.

2. The combination, in an Argand-lamp burner, of an air-tube closed at the bottom, a wick-tube around the air-tube with an intermediate space for a flat wick bent to a cylindrical form, a lateral air-inlet, a wick-raising ring having outwardly-projecting teeth and sliding on the air-tube, means for moving the wick-raising ring, and a removable section at 75 the upper part of the wick-tube, substantially as set forth.

3. The supplemental air-distributer *l*, in combination with the wick-tube, air-tube, removable chimney-holder, air-distributer, and deflector of an Argand burner, such supplemental air-distributer surrounding the wick-tube at the base of the deflector, and serving also to steady the removable portions of the burner, as set forth.

4. The combination, with the Argand burner having a button, of a sliding extinguisher-sleeve surrounding the wick-tube, and means for raising the extinguisher to the button, substantially as set forth.

5. The extinguisher-sleeve *m*, having a downwardly-projecting leg, *6*, in combination with the wick-tube, the supplemental air-distributer *l*, through which the leg of the extinguisher passes, and the cam-arm *o'* and its actuating-shaft, substantially as set forth.

6. The combination in an Argand-lamp burner, of an air-tube, a wick-tube having a removable section, a wick-raiser around the air-tube, and means for actuating the same, a sliding extinguisher-sleeve around the wick-tube, and means for moving such extinguisher, substantially as set forth.

7. In combination with the air and wick tubes in an Argand burner, a deflector surrounding 105 and near the top of the Argand wick, and having a vertically-hanging cylindrical flange within its upper end, for the purposes and as set forth.

8. The combination, in an Argand lamp, of 110 a deflector having a hanging flange at its upper end and holes near the base of the deflector, a chimney-holder, and air-distributer formed of a cylinder around the deflector, and a supplemental air-distributer within the base 115 of the deflector, substantially as set forth.

Signed by me this 8th day of November, A. D. 1880.

H. W. HAYDEN.
